UNITED STATES PATENT OFFICE.

CHARLES R. BURKE, OF TULSA, OKLAHOMA.

PROCESS FOR MAKING PETROL OR GASOLINE.

1,344,258.

Specification of Letters Patent. Patented June 22, 1920.

Application filed December 8, 1910, Serial No. 596,382. Renewed May 18, 1920. Serial No. 382,335.

To all whom it may concern:

Be it known that I, CHARLES R. BURKE, citizen of the United States, residing at Tulsa, in the county of Tulsa and State of Oklahoma, have invented certain new and useful Improvements in Processes for Making Petrol or Gasolene; and I do hereby declare the following to be a full, clear, and exact description of the invention, such as 10 will enable others skilled in the art to which it appertains to make and use the same.

My invention consists of certain new and useful improvements in the art of making petrol or gasolene, whereby a product is obtained having a greater number of thermal units, and at a reduced cost of production.

My process consists in distilling crude oil in any well known manner and preferably under from twenty-five (25) to one hundred 20 (100) pounds pressure, and then mixing, with the resulting vapor, natural gas, then compressing the combined vapor and natural gas and then condensing said mixture; the product will be my improved gasolene.

25 The amount of pressure in the still depends upon the character of the material with which the still is originally charged and is to be determined by experiment with each different quality of oil to be distilled.

30 The vapor from the still may be carried to a mixing chamber into which natural gas is also introduced, and thence with the gas to a compressor by which the mixed vapor and gas are compressed. The compressed 35 vapors are then led to a condenser where all possible condensation is effected and the condensate is then run off into a receiving reservoir from which it may be drawn for use. The reservoir is provided with a pressure valve which registers the amount of 40 pressure in the condenser, and the amount of pressure is determined by the desired quality of the condensate.

In carrying out my process, I may find it 45 desirable to distil the crude oil one or more times, passing the resultant vapors of the first distillation through a condenser into a container, then distilling the product of the first distillation in the same way, and so on, 50 distilling the product of the last distillation under varying degrees of pressure as has already been stated, after which the natural gas may be mixed with the vapor or gas derived from the steps of my process just described and the combination of the vapor

and natural gas is then condensed into gasolene.

The natural gas is preferably mixed with the vapor before the latter enters the condenser and may be forced into the condenser 60 under a pressure equal to or exceeding the pressure of the vapor, or the vapor and natural gas may be intermingled in a container by means of baffles, etc., so as to insure a complete mixture at the time of condensation. 65

My invention also contemplates taking what is now uncondensed vapor, arising from the ordinary distillation of crude oil and its products mixing therewith natural 70 gas and condensing same under pressure into gasolene.

In order that my invention may be clearly understood I have illustrated diagrammatically one form of apparatus which may be 75 used for carrying out my process, in which similar letters of reference indicate identical parts.

A is a still, constructed of any suitable material, which is capable of withstanding 80 an internal pressure of from twenty-five to one hundred pounds to the square inch. B is a heating means of any desired form for heating the contents of the still.

C is what I may term a mixer, and consists of a chamber or compartment, constructed of any suitable material in which the vapors from the still are mixed with natural gas. The temperature of the chamber C is maintained preferably at a temperature of about 300° Fahrenheit. 85

a, a', a'' are tubes leading from the still to the mixing chamber, and in the tube a'' I provide a pressure valve D. E is a tube which is connected with an oil well and 90 through which natural gas may be inducted to the mixing chamber C under a pressure sufficient to force the gas into the said chamber.

F is a condenser of usual form and G is 100 a pump for drawing the vapors from the mixing chamber C into the condenser F through suitable connections I, K, the pressure exerted by the pump or compressor being regulated by the specific gravity desired for the resultant product. 105

It will be understood of course, that there are suitable check valves arranged in the pipes between the condenser and pump and mixer and pump to permit the vapors to be 110

drawn by the pump from the mixer and forced into the condenser, but preventing vapors being withdrawn from the condenser and forced back into the mixer.

5 H is a reservoir for receiving the product which is gasolene, from the condenser. The reservoir is also provided with a pressure valve K'.

In operating the above described form 10 of apparatus, oil is placed in the still, and the pressure valve D adjusted so as to permit the discharge of vapor into the mixing chamber at a given pressure which may be from twenty-five to one hundred pounds.

15 Heat is then applied to the still and distillation ensues.

There is necessarily some pressure in the mixing chamber C and I preferably arrange 20 to force natural gas into said chamber simultaneously with the admission of vapor from the still, and the said vapor and gas are there mixed. The mixture is then forced into the compressor and thence into the condenser and the condensed product or 25 gasolene run off into reservoir H.

As formerly stated, I may distil and re-distil the crude oil until a vapor of sufficient lightness is obtained before mixing the same with the natural gas in the mixing 30 chamber.

Broad claims covering the same general subject matter of this invention, are being prosecuted in a co-pending application.

What I claim and desire to secure by Letters Patent is:—

1. The process of making gasolene from heavier hydrocarbon oil which consists in distilling such heavier hydrocarbon oil under pressure, then mixing natural gas with the vapor resulting from said distillation, 40 then passing the combined vapors through a compressor and then condensing the same.

2. The process of making gasolene from heavier hydrocarbon oil which consists in distilling such heavier hydrocarbon oil, 45 condensing the resultant vapors and redistilling the same until a vapor of the desired lightness is obtained, mixing natural gas with the said vapor, then passing the resultant vapor through a compressor and then condensing the same.

3. The process of making gasolene from heavier hydrocarbon oil which consists in distilling such heavier hydro-carbon oil, 55 then mixing natural gas with the vapor resulting from said distillation, then passing the combined vapors through a compressor, as heretofore described, and then condensing the combined condensable vapors.

In testimony whereof I affix my signature, 60 in the presence of two witnesses.

CHARLES R. BURKE.
